GAME BOARD DEVICE

Oscar Mautner, Crestwood, and Mark K.
Lebwirth, New York, N. Y.

Application June 19, 1944, Serial No. 540,962

5 Claims. (Cl. 273—113)

1

This invention relates to a gameboard device. It is an object of the invention to provide a device for playing a game which will incorporate a high degree of skill and dexterity in manipulation, and also will provide means for holding the interest of the participants, in order that the participants will be induced continuously to apply themselves, particularly as the game is designed for exercising the muscles of the fingers, hands and arms of injury or partial paralysis cases.

It is an object of the invention to provide a gameboard for a game wherein is incorporated the interest of fitting a "square peg into a round hole."

It is an object of the invention to provide, for a game of the type indicated, a gameboard having a plurality of recesses or depressions, wherein a distinctive contouring is imparted to the various recesses, or groups of recesses, and one or more playing pieces, wherein the various pieces, or groups of pieces, have distinctive shaping, so that each playing piece may interfit with and become nested in one or more of the recesses in the board. Thus, this cooperation of playing piece and recess gives rise to a game of skill in manipulation of the board to bring the playing piece to rest with one of its contours interfitted with one of the recesses.

Other objects of this invention will be set forth hereinafter, or will be apparent from the description and the drawing, in which are illustrated embodiments of apparatus exemplifying the invention.

The invention, however, is not intended to be restricted to any particular construction, or any particular application of such construction or arrangement of parts, or any specific method of operation, or any of various details thereof, even where specifically shown and described herein, as the same may be modified in various particulars, or may be applied in many varied relations, without departing from the spirit and scope of the claimed invention, practical constructions embodying certain details of the invention being illustrated and described, but only for the purpose of complying with the requirements of the statutes for the disclosure of operative embodiments, but without attempting to disclose all of the various forms and modifications in which the invention might be embodied.

On the drawing, in which the same reference characters refer to the same parts throughout, and in which are disclosed such operative embodiments,

2

Fig. 1 is a plan view of a gameboard embodying features of the invention;

Fig. 2 is a vertical cross-sectional view, taken along the longitudinal axis of the gameboard shown in Fig. 1;

Fig. 3 is a perspective view of a playing piece to be used together with the gameboard shown in Fig. 1;

Fig. 4 is an elevational view of another type of playing piece for the same purpose;

Fig. 5 is a view of another type of playing piece for that purpose; and

Fig. 6 is a cross-sectional view, taken transversely and longitudinally of the playing piece shown in Fig. 3, the ball being shown in elevation.

Gameboard 10, shown on the drawing, may comprise a slab 12 of any desired material. For instance, slab 12 may be formed by being cut out 20 of plywood, or it may be molded from plastic. Any suitable design may be utilized in determining the outer bounds of the board. The dimensions of the slab, such as thickness and total extent, are determined by factors such as the weight of the particular material from which the slab is made, in relation to bulkiness, for proper manipulation. Slab 12 may have a handle 14 for control of the slab during the various manipulations necessary for the game, when played in the manner to be described. A wall 16 may be provided to define the limits of the playing area 18. Wall 16 may comprise an integral part of slab 12, or it may be constructed from a strip 20 of metal, suitably secured against and to the peripheral face 22 of slab 12. A groove 24 may be cut in slab 12 so that strip 20 may extend continuously across handle 14. Strip 20, seated and retained in groove 24, thus provides a substantially continuous wall around playing area 18.

Area 18 may be divided into a plurality of different fields; in the structure shown, two different surfaces 26 and 28 are shown. These surfaces, as shown in Fig. 2, are at two different levels. Surface 26 may be above surface 28, with a ledge 30 between the two surfaces.

Surface 26 may be provided with a plurality of different types of depressed areas. For purposes of illustration, five types of such depressions or recesses 32, 34, 36, 38 and 40 are shown; that is, 50 many of the recesses may be identical in form, but those here designated are taken to be representative. Such various representative recesses may be dispersed throughout the extent of surface 26 according to any desired plan. Associated with 55 each recess may be an indication 42 of the num-

ber of points awarded to a player when he attains a result such as to be described further herein.

The recesses may be formed or provided in the gameboard by being molded simultaneously with the formation of slab 12; or, as, for instance, where the slab is made from material such as plywood, the recesses may be produced by proper manipulation of wood turning or working tools.

Some of the recesses may be similar to recesses 32. Such recess may be substantially hemispherical in shape. Some of the recesses may take the form of recess 34, which, as appears from Figs. 1 and 2, is substantially square in plan. The mouth 44 of recess 34 may be tapered, as illustrated in Figs. 1 and 2, to facilitate cooperation with the playing piece, in the course of the game to be described. Recesses 34 and 36 may be substantially identical in plan and other structural details. However, as appears from Fig. 1, the diagonal of the square, in the case of recess 34, may be substantially parallel to the longitudinal axis of gameboard 10. In the case of recess 36, the diagonal of the recess may be diagonal to that longitudinal axis.

As for recesses 38 and 40, a different effect is produced. Each of these recesses includes a substantially hemispherical portion 46 opening at surface 26. Extending downwardly from and opening into the contour of the hemispherical portion 46 is a terminal portion 48 for each recess 38 and 40. This terminal portion is square in plan, as are recesses 34 and 36. Furthermore, just as the diagonals of recesses 34 and 36 were disposed in different angular relations to the axis of the gameboard, so are the diagonals of recesses 38 and 40 arranged in different angular relations to the axis of the gameboard.

In Fig. 3, a playing piece 50, intended to be placed on surfaces 26 and 28, is shown. More than one of these pieces may be disposed on surface 26 at any one time. Also, piece 50 may be used with or without the presence of other pieces, for instance, pieces 52 and 54 such as shown in Figs. 4 and 5.

The ends 56 and 58 of piece 50 may have different contours. For instance, end 56 may be substantially a hemisphere; end 58 may be substantially cubical. Of course, the intersections of corners 60 with bottom 62 of end 58 and bottom 62 itself may be rounded off, as shown, but merely to facilitate rolling of piece 50 on end 58 in the manner to be described. Beyond the hemisphere of end 56, the body of piece 50 may take the form of a cylindrical extension 64 of the hemisphere, that is, the body may be of substantially circular cross-section, the cross-section being of a diameter substantially the same as that of the hemisphere. A fillet or shoulder 66 may be formed between extension 64 and the body of end 58. The length of end 58 and extension 64 is greater than the total length of end 58, for a purpose to be described.

Piece 50 is hollow, and has a cavity 68 in which a ball 70 may be disposed. Cavity 68 extends between ends 56 and 58, so that ball 70 may move freely from end to end in the cavity. The effect of ball 70, which is of predetermined weight and heavier than the material of which the piece is formed, is to transfer the center of gravity from end to end as it moves through the cavity, causing piece 50 to stand up, first on one end, and then on the other. Thus, as the one playing the game holds slab 12 by handle 14, and vibrates the slab thereby, tipping and tilting it at the same time, piece 50 will sway, turn end over end, roll, and

produce many other motions, some capable of control, and some incapable of prediction. As ball 70 rolls through cavity 68, and changes the center of gravity of the whole unit, the piece will tend to rise, first to rest upon the hemispherical portion, and then to rest upon the cubical portion. Because of the greater length of end 58 and extension 64, the ball will be prevented from maintaining piece 50 with the ball permanently in that end of the cavity at end 58.

The manipulator will try to move the board and the piece so that end 58 will come to rest in recesses 34 and 36, for which a substantially higher score may be allowed, by the rules of the game, than when the piece comes to rest with end 56 in a recess 32. Likewise, different scores may be allowed when end 58 of the piece interferes with terminal portions 48 of recesses 38 and 40. If any of the pieces should pass off over ledge 30 from surface 26 onto surface 28, a penalty may be imposed.

Pieces 52 and 54 likewise may be formed with cavities, and may have members similar to balls 70 for changing their centers of gravity. In these cases, however, the cross-section of the piece is substantially uniform. In the case of piece 52, both ends are hemispherical, being connected by a portion 72 which may be cylindrical and substantially of the same diameter as the ends, or it may be of reduced diameter. In the case of piece 54, the ends are similar to ends 58, being substantially square in cross-section, and having a connecting body 74 of substantially the same cross-section throughout. Different scoring may be arranged and allowed when either of these pieces nests in the particular recesses 32, 34, 36, 38 and 40.

Pieces 50, 52 and 54 may be made in any desired manner. The same plan of construction may be followed in all cases. For instance, piece 50 may be formed of two sections 76 and 78, and both sections may be molded from plastic. One section 76, at the open end 80, may have a collar 82, and a shoulder 84 disposed outside the collar. Section 78 would then have a reverse formation, with a shoulder 86 within a flange 88. These portions are so designed that flange 88 will fit around collar 82. By means of a plastic solvent such as acetone, the parts may be cemented together after a ball 70 has been positioned within the cavity.

The participants in such a game are induced to develop a high degree of dexterity and skill as they manipulate the gameboard to keep the playing pieces out of area 28; while manipulating them to stand up and seat within the desired scoring recesses. Of course, such manipulation necessarily induces desired exercising of muscles of fingers, hand and arm. Of course, as the pieces roll over surface 26, it will be the endeavor of the player to fit a square peg into a square hole, for the best score, and to avoid fitting a round peg into a square hole.

Many other changes could be effected in the particular apparatus, and in the particular products, and in the methods of operation, use and construction, and in specific details thereof, hereinbefore set forth, without substantially departing from the invention defined in the claims, the specific description being merely of embodiments capable of illustrating certain principles of the invention.

What is claimed as new and useful is:

1. In a gameboard device, a gameboard including a substantially flat playing surface, a playing

piece for disposition upon the playing surface, the surface having a plurality of indentations formed therein, means for manipulating the gameboard to cause the piece to move over the playing surface, and means for retaining the piece against movement off the surface, the piece including portions each of a distinctly different contour from that of another portion, and certain of the indentations having a form distinctly different from the form of others of the indentations, each contour of a portion of the piece being complementary to at least one of the forms of the indentations.

2. In a gameboard device, a gameboard including a substantially flat playing surface, a playing piece for disposition upon the playing surface, the surface having a plurality of indentations formed therein, means for manipulating the gameboard to cause the piece to move over the playing surface, and means for retaining the piece against movement off the surface, certain of the indentations having a form distinctly different from the form of others of the indentations, at least one of the indentations being of a spherical form, one end of the piece having a non-spherical contour complementary to the form of at least one of the indentations so that the piece may come to rest and nest in at least one of the indentations, the other end of the piece having a substantially spherical contour.

3. In a gameboard device, a gameboard including a substantially flat playing surface, a depressed area beyond the flat surface, the playing surface providing a shoulder between the surface and the area, a playing piece for disposition upon the playing surface, the substantially flat playing surface having a plurality of indentations formed therein, and means for manipulating the gameboard to cause the piece to move over the playing surface, at least one of the indentations having its contour made up of portions of a plurality of distinctly different forms, one portion of the piece having a contour complementary to only one of the forms of

said indentation so that the piece may come to rest and nest in said indentation but only in association with the complementary contour.

4. In a gameboard device, a gameboard including a playing surface, a playing piece for disposition upon the playing surface, the surface having a plurality of indentations formed therein, and means for manipulating the gameboard to cause the piece to move over the playing surface, the piece having a pair of ends and including means for controlling the center of gravity of the piece so that the piece will come to rest substantially on one of its ends, each end of the piece having a contouring distinctively different from the contouring of the other end, and certain of the indentations having a form distinctively different from the form of other indentations, each end of the piece being designed to interfit with at least one of the distinctively different contourings of the indentations.

5. In a gameboard device, a gameboard including a playing surface, a playing piece for disposition upon the playing surface, the surface having a plurality of indentations formed therein, and means for manipulating the gameboard to cause the piece to move over the playing surface, the piece comprising a hollow body and having a pair of ends, and means within the hollow of the body for controlling the center of gravity of the piece so that the piece will come to rest substantially on one of the ends, each end of the piece having a contouring distinctively different from the contouring of the other end, and at least one of the indentations comprising a recess of one form, and another recess of a different form opening from the first mentioned recess, the contouring of one of the ends of the piece being complementary to and designed to interfit with one of said recess and the contouring of the other end of the piece being complementary to and designed to interfit with the other of the recesses.
